UNITED STATES PATENT OFFICE.

HENRY CLAY BENTON AND JOSEPH RICHARD VEST, OF HUNTINGTON, WEST VIRGINIA.

AUTOMOBILE-PULLER.

1,270,104.

Specification of Letters Patent. Patented June 18, 1918.

Application filed September 5, 1917. Serial No. 189,837.

To all whom it may concern:

Be it known that we, HENRY C. BENTON and JOSEPH R. VEST, citizens of the United States, residing at Huntington, in the county of Cabell and State of West Virginia, have invented new and useful Improvements in Automobile-Pullers, of which the following is a specification.

This invention relates to pulling implements, and more especially to those employing a cable and drum which latter is motor-actuated; and the object of the same is to produce a device for pulling a motor vehicle out of the mud or sand when it becomes stalled therein.

The invention comprises an extension at the front end of the engine shaft and a worm on said extension, a drum having a worm gear, and means for throwing the gear into mesh with the worm when the puller is to be used—all as hereinafter more fully described and claimed and as shown in the drawings wherein:—

Figure 1 is a perspective view of the front end of a well-known type of automobile with this device applied thereto but with its parts turned so that the gear is out of mesh with the worm and the device is inactive.

Fig. 2 is an enlarged side elevation, with parts partly broken away and in section.

Fig. 3 is a transverse section on the line 3—3 of Fig. 2.

We are not concerned with any part of the motor vehicle excepting its frame F and its main or driving shaft S and cranking handle C, and while we have shown this attachment applied to one form of car, it is quite obvious that it could be adapted to a variety of cars without departing from the principle of the invention. It is well known that, especially where a motor vehicle is used on muddy, sandy, or otherwise bad roads, it is quite apt to become stalled so that the driver can not

start the machine by the traction of its driving wheels—due either to the bad condition of the roadway, the excessive load, or both. To meet this contingency, devices have been made which pull the machine out of a rut by winding upon a drum a rope or cable which is carried forward and attached to some fixed object such as a pin driven in the ground, a tree or fence post, or the like. Our invention is of that type which employs a drum 1 whereon is wound a rope 2, and it is hardly necessary to illustrate the pin or

tree to which the front end of the rope must be attached when it is to be used. When not in use the rope is wound upon the drum and the latter stands idle. When the attachment is in use, the drum must be connected with the main or crank shaft so that when the engine is started the drum is rotated, the rope having been first unwound and paid out to a considerable extent—all as well understood and needing no further reference herein.

We provide a pair of bracket arms 3 to overlie the front cross bar of the frame F, each having a clip plate 4 and bolts 5 or other suitable means for attaching it to the frame F of the machine, and these elements constitute the framework on which the structure described below is mounted. Journaled in suitable bearings 6 on the framework is an extension shaft 7 whose rear end 8 has suitable means for connecting it to the front end of the crank shaft S and whose front end herein is shown as provided with a pin 9 adapted to be engaged by the hub 80 of the crank handle C as the latter is applied—see dotted lines in Fig. 2. We do not wish to be confined to details, but the idea here is that the framework supports an extension shaft 7 by means of which the main or engine shaft S is elongated or carried to some little distance forward of the radiator, and the front end of this extension shaft may be provided with means whereby the crank handle can be used as customary, in case the motor vehicle is not provided with a self-starter.

Fast on the extension shaft is a worm 10. Mounted in other bearings 11 and 12, carried by appropriate parts of the framework 95 is a cross shaft 13, and fast on this shaft is a drum 14 and a worm gear 15, the latter standing over the worm and having its teeth properly shaped to engage therewith. The cross shaft is loose in its outer bearing 11, 100 and is journaled eccentrically in a sleeve 16 which latter in turn is journaled in the inner bearing 12, and from the sleeve rises a handle 17 in the shape of a lever having a hand-grip or handle proper 18 at its upper end which is of some considerable weight. We prefer to so dispose this lever 17 and its handle 18 with respect to the sleeve 16 that when the handle stands upright or nearly so the eccentric bearing through the sleeve 110 is at the lower portion thereof and the worm gear is in mesh with the worm as seen in

Figs. 2 and 3, but when the lever is turned forward and downward, the sleeve is turned within the bearing 12 so that the inner end of the cross shaft and the worm gear are raised 5 and the attachment is thrown out of engagement with the worm. In other words, the normal pendent position of the weighted lever 17 is such that it holds this attachment out of action, but when the lever is swung 10 forward and upward and its handle 18 is laid back against the radiator, the attachment is in action. This detail is purposely adopted because when the attachment is at work any sudden stoppage of the automobile 15 in its forward progress will cause the handle to move forward by inertia and throw the puller out of action before the cable is broken. It is our intention that this attachment shall be applied to and become a per- 20 manent part of the automobile as seen in Fig. 1, although of course it is optional with the user to take it off his car in case he intends to travel on good roads or for pleasure, while he will doubtless employ it at all times 25 when he expects to travel on poor roads or with a heavy load or both.

The use of automobile pullers of this kind is now very well known. In case the machine becomes stalled, the driver dis- 30 mounts, carries the forward end of the cable up the road or along the road and attaches it to some fixed object such as a pin, a tree, or a fence post, then cranks the engine as usual. Next he swings the lever for- 35 ward and upward and throws the handles back against the radiator and gets out of the way, and thereafter the power of the main shaft is communicated by the gear and gearwheel to the drum 14 which begins to 40 rotate slowly. As soon as the slack on the cable is taken up, further movement of the drum winds the cable thereon with the result that the automobile is pulled out of the stalled position by its own power. After 45 having gotten out of the rut the engine is stopped, the lever turned back to the position shown in Fig. 1 which loosens the drum, the cable loosened up and detached or disconnected from the stump or pin and 50 rewound, and the driver proceeds on his way. In case the car or machine is pulled out of the rut with a rush and comes up against some obstruction, the inertia of the rather heavy handle 18 will cause it to move 55 forward when the car stops, with the result that it will fall over to the front and carry the lever 17 with it and disengage the worm-gear from the worm so as to put this attachment out of action without necessarily 60 drawing the machine over the obstruction to the injury of parts in case the obstruction

should be a stump. Of course this device is capable of other uses. For instance, the motor vehicle could be stopped on the road and the cable paid out to another machine which 65 was in similar trouble, and the first machine with brakes set could act as a power-driven windlass to draw the second out of its stalled position. Or, of course any work could be 70 performed by this attachment properly applied to a machine, which would be susceptible of performance by drawing forcibly on a cable. The parts are all of metal, easily manufactured and readily applied, and the attachment should not be heavy or expensive. 75

What we claim as new is:—

1. The herein described automobile puller comprising a framework adapted for attachment to the frame of the motor vehicle, a sleeve journaled in the framework and having through it an eccentric bearing, a cross shaft journaled in this bearing and carrying a drum, a cable attached to said drum and adapted to be wound thereon, a worm gear fast on the shaft, a worm driven 85 by the main shaft of the vehicle, and a lever projecting radially from said sleeve and having a weighted handle at its outer end, the position of said lever with respect to the sleeve being such that when the lever is 90 raised and thrown back against the radiator the gear is thrown into mesh with the worm for the purpose set forth.

2. The herein described automobile puller comprising a framework adapted for attachment to the frame of the motor vehicle, an extension shaft journaled in said framework and adapted for attachment at its rear end to the main shaft of said vehicle, the extension shaft also adapted for the attachment to its front end of the cranking handle, a worm on said shaft, bearings carried by said framework, a sleeve journaled in the inner bearing and having through it an eccentric bearing, a cross shaft journaled in this bearing and in the other bearing first mentioned, a drum fast on said shaft between its bearings, a cable attached to said drum and adapted to be wound thereon, a worm gear also fast on said shaft above the 105 worm, and a lever projecting radially from said sleeve and having a weighted handle at its outer end, the position of said lever being such that when raised and thrown back against the radiator the gear is thrown 110 into mesh with the worm, for the purpose set forth.

In testimony whereof we affix our signatures.

HENRY CLAY BENTON.
JOSEPH RICHARD VEST.
